US0D1029578S

(12) **United States Design Patent** (10) **Patent No.:** **US D1,029,578 S**
(45) **Date of Patent:** **** Jun. 4, 2024**

(54) **CUP COVER**

(71) Applicant: **Dinglin Li**, Hanzhong (CN)

(72) Inventor: **Dinglin Li**, Hanzhong (CN)

(**) Term: **15 Years**

(21) Appl. No.: **29/826,041**

(22) Filed: **Feb. 9, 2022**

(30) **Foreign Application Priority Data**

Nov. 12, 2021 (CN) 202130742732.9

(51) **LOC (14) Cl.** **07-10**

(52) **U.S. Cl.**

USPC **D7/396.2**; D7/392.1

(57) **CLAIM**

The ornamental design for a cup cover, as shown and described.

DESCRIPTION

FIG. 1 is a perspective view of a cup cover showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view of thereof; and,

FIG. 8 is a bottom plan view of thereof.

The broken lines depict portions of the cup cover that form no part of the claimed design.

1 Claim, 8 Drawing Sheets
